LEVER OPERATOR FOR JALOUSIE WINDOWS

Charles E. Spencer, Chicago, Ill., assignor to The Casement Hardware Co., Chicago, Ill., a corporation of Illinois

Filed Feb. 9, 1960, Ser. No. 59,324

Term of patent 14 years

(Cl. D10—10)

FIGURE 1 is a front elevational view of a lever operator for jalousie windows, showing my new design;

FIGURE 2 is a view similar to FIGURE 1 but at an enlarged scale thereover;

FIGURE 3 is a top plan view of the same;

FIGURE 4 is a perspective view thereof; and

FIGURE 5 is an end elevational view of the same, looking at its left hand end as oriented in FIGURES 1 and 2. The broken line portion in FIGURE 1, representing a bank of jalousie windows, is for illustrative purposes only.

I claim:

The ornamental design for a lever operator for jalousie windows, substantially as shown and described.
